United States Patent Office.

CLOVIS LOWE, OF RANDOLPH, NEW HAMPSHIRE.

Letters Patent No. 96,934, dated November 16, 1869.

IMPROVEMENT IN FENCE.

The Schedule referred to in these Letters Patent and making part of the same.

To all whom it may concern :

Be it known that I, CLOVIS LOWE, of Randolph, in the county of Coos, and State of New Hampshire, have invented a new and useful Improvement in Fences; and I do hereby declare that the following is a full, clear, and exact description of the same, reference being had to the annexed drawings, making part of this specification, in which the fence is shown in a side elevation.

My improvement consists in attaching a post-foot made of concrete, to a wooden post, by means of a dowel-pin, for the purpose of permanently supporting a fence upon a post-foot not subject to decay, and which may be constructed in a country where stone cannot be obtained.

In the annexed drawings—

A represents a foot-post, formed by pouring concrete into a hole in the ground, and fixing therein an iron dowel-pin, placed perpendicularly, and allowing the concrete to remain until it becomes hard.

When this is done, the posts C, to which are at-

tached the panels E, may be set, by inserting the dowel-pin B into a hole, D, formed in the bottom of the post.

By this means, I provide a post-foot that is not liable to decay, and, keeping the wooden post away from contact with the earth, preserves it from decay.

The concrete post-foot may be removed in case the line of fence requires to be changed.

What I claim as my invention, and desire to secure by Letters Patent, is—

The combination of the post-foot A, the dowel-pin B, post C, constructed with a hole, D, in the base, and panel E, substantially as and for the purpose set forth.

In testimony whereof, I have signed my name to this specification, in the presence of two subscribing witnesses.

CLOVIS LOWE.
